United States Patent Office.

DAVID NEUMANN, OF NEW YORK, N. Y.

Design No. 3,381, dated February 16, 1869.

DESIGN FOR A SATCHEL-LOCK

The Schedule referred to in these Letters Patent and making part of the same.

To all whom it may concern:

Be it known that I, DAVID NEUMANN, of New York, in the county and State of New York, have originated and designed a new Design for a Lock for Satchels, Carpet-Bags, &c., of which the following is a full, and clear, and exact description, reference being had to the accompanying drawings, making part of this specification.

This invention is applicable to all descriptions of locks for satchels, carpet-bags, &c., wherein the bolt in the inside of the lock, which opens or shuts the lock, is operated on the side of the lock-case, on the outside, by connecting said bolt, by means of a pin or its equivalent, with a projection on said side of the casing.

The ornament or configuration of this projection forms the nature of my invention, and the same consists of the arrangements of two flags, *a a*, represent-

ing the American flags, the flag-staffs of which cross each other, so that one flag will be suspended toward the right, and the other flag toward the left side.

Between the two flags, resting upon their flag-staffs, a bird, *b*, representing an eagle, is arranged, with a small American shield on its chest. The flags and eagle are made in alto-relievo, and may be burnished, or the flags may be enamelled and the eagle burnished, or both flags and eagle may be enamelled.

What I claim as my invention, and desire to secure by Letters Patent, is—

The ornament or configuration on the side of a lock for satchels, &c., herein set forth.

DAVID NEUMANN.
